Attorney

UNITED STATES PATENT OFFICE.

OTTO RÖSEKE, OF STUTTGART, GERMANY.

ALARM CLOCK.

1,424,214.

Specification of Letters Patent. Patented Aug. 1, 1922.

Application filed February 13, 1920. Serial No. 358,490.

To all whom it may concern:

Be it known that I, OTTO RÖSEKE, a citizen of the German Republic, residing at Stuttgart, Württemberg, Germany, have in-

5 vanted certain new and useful Improvements in Alarm Clocks (for which I have filed application in Germany October 23, 1919, Patent No. 326,502), of which the following is a specification.

10 This invention relates to alarm clocks and more particularly to an alarm clock having a preliminary or warning alarm for the purpose of awaking a person from a light slumber without awaking others in the 15 vicinity. Such an alarm clock is disclosed in my application Serial No. 303,493 filed June 11, 1919, and this present application in some respects may be considered an improvement on the alarm clock therein dis- 20 closed.

In my aforesaid application, there is provided a special controller for bringing the preliminary alarm into action and for variably controlling the nature of the alarm as 25 the period for the regular alarm is approached, being in addition to the controller of the usual alarm.

The present invention has obviated the necessity of providing two controllers for 30 the two alarm mechanism and in so doing has materially simplified the structure of the clock, making it more positive and reliable in operation and more economical to manufacture. This has been done by pro- 35 viding means on the usual alarm controller for reaching to and controlling the preliminary alarm. It should be noted in connection with the above that the device in my aforesaid application is efficient and satis- 40 factory and that the present invention is a further step in advancement to perfection. It should also be noted that in the clock and watch industries where the articles are manufactured by the thousands, even a 45 slight saving in material and labor on each article is an important advantage in itself.

The present invention has a further improvement, namely, the provision of a stamped star wheel for actuating the preliminary alarm instead of the pegged wheel used in the clock of my aforesaid application.

In the accompanying drawings which show by way of example one embodiment of my 55 invention:

Figure 1 is a front view of an alarm clock

showing my invention applied thereto, the parts not essential to the understanding of the present invention being omitted.

Fig. 2 is a detail view of the controller. 60

Fig. 3 is another detail of the controller, looking at the same from above.

Fig. 4 is a plan of such portions of the alarm clock as are necessary to the understanding of this invention. 65

Fig. 5 is a front view similar to Fig. 1, but showing the preliminary alarm mechanism in the position it occupies except when functioning.

Before describing the structure of the 70 illustrated embodiment of the present invention, attention is called to the fact that the continuous or usual alarm may be of the conventional or usual type having its own usual or conventional hammer operating 75 mechanism.

As illustrated, the hammer *a* of the preliminary alarm is mounted on a pivot *b* and is weighted on one side so as to have a normal tendency to fall against and strike 80 a blow on the usual bell *c* to give single stroke signals.

Depending from the hammer *a* there is a wire or other suitable arm *e* having at its lower end a head *e*¹, adapted to move into 85 the path of a star wheel *d* which is connected by gears *i* and *h* to the time work mechanism of the clock so as to continuously rotate. The star wheel *d* takes the place of and is operated in the same manner 90 as the pegged operating wheel of the clock of my aforesaid application and similarly serves as the means for moving the hammer to position from which it will fall to strike the bell when released. 95

The controller *g* for the usual alarm mechanism is constituted by a spring secured at its lower end to the frame work and engaging at its upper end the time wheel 1 of the usual alarm mechanism. 100 The controller *g* has a lug 2 bent from its upper end for engaging and releasing the usual alarm mechanism at the proper time when a notch 3 in the time wheel 1 is opposite a pin 4 of the alarm setting mechanism, the notch 3 permitting the controller to move sidewise to withdraw the lug 2 and permit the usual alarm to operate. In accordance with my aforesaid invention, the notch 3 is not abrupt as is usual in alarm 110 clocks but has a gradual slope for the purpose of gradually increasing the force of

impact of the hammer *a*. Thus the time wheel 1 and the controller *g* will be gradually moved to withdraw its lug 2.

The present invention provides upon this controller *g* another lug, lug *f* which reaches to and engages the arm *e* of the hammer *a* so that the hammer can be controlled thereby. The portion of the lug *f* which engages the arm *e* is sloping so that as the controller *g* is permitted to move by the slope on the time wheel 1 the range of movement of the hammer is gradually increased with the effect that the force of impact of the hammer against the bell increases. When the preliminary alarm is functioning the star wheel *d* engaging the head *e*¹ of the arm *e* raises the hammer weight and then releases it, the sloping lug *f* on the controller *g* limiting the return movement of the hammer and thus modifying the effective impact of the hammer. As the time progresses the lug *f* gradually permits a greater movement of the hammer and thus causes the sound of the bells to be louder. During the greater part of the time, that is when the preliminary alarm

is not functioning, the lug *f* holds the arm *e* in the position shown in Fig. 5 in which the head *e*¹ is out of the range of the star wheel and therefore is not operated thereby. 30

The usual or conventional means for rendering the alarm ineffective may be used.

Variations may be resorted to within the scope of my invention and portions of the improvements may be used without others. 35

I claim as my invention:—

In an alarm clock, a preliminary alarm mechanism comprising an alarm operating arm, a hammer connected thereto, a head carried by said arm; time works comprising 40 a gear-wheel; and a star wheel geared to said gear wheel and adapted to engage the head carried by the alarm operating arm to move said arm in preparation to giving an alarm and to subsequently release said arm 45 to cause the alarm to be given.

In testimony whereof I affix my signature in presence of two witnesses.

OTTO RÖSEKE.
